His Attorney.

UNITED STATES PATENT OFFICE.

CLARENCE T. CROCKER, OF SCHENECTADY, NEW YORK, ASSIGNOR TO GENERAL ELECTRIC COMPANY, A CORPORATION OF NEW YORK.

MOTOR CONTROL.

1,334,134.

Specification of Letters Patent. Patented Mar. 16, 1920.

Application filed August 15, 1918. Serial No. 250,050.

To all whom it may concern:

Be it known that I, CLARENCE T. CROCKER, a citizen of the United States, residing at Schenectady, county of Schenectady, State of New York, have invented certain new and useful Improvements in Motor Control, of which the following is a specification.

My invention relates to controllers for electric motors and has for its object the provision of means whereby a controller may be limited to a slow movement or, if desired, may be operated rapidly.

My invention relates more specifically to a controller of the type which it is desired should be limited to a step-by-step forward movement, means being provided whereby, if desired, continuous movement may be substituted for the step-by-step movement. In one embodiment of my invention I have provided a controller which is moved forward by the back-and-forth movement of the operating handle, one step being taken each time the controller handle is moved back and forth or, if desired, the operator by applying more pressure to the operating handle may rapidly move the controller with a continuous movement of the operating handle.

My invention will be best understood from the following description taken in connection with the accompanying drawings in which Figure 1 is a plan view of the controller with part of the mechanism broken away; Fig. 2 is a side view of the same with the frame removed, and Figs. 3 and 4 show details of construction.

Referring to the drawings, 10 is the operating handle pivoted at 10' by which the controller shaft 11 is operated. This operation takes place either slowly through the ratchet segment 12 to which is secured the gear 13 meshing with the pinion 14 on the controller shaft or through the gear sector 15 meshing with a pinion 16 on the controller shaft. It will be noted that there is a higher gear ratio between the sector 15 and pinion 16 than between the gear 13 and pinion 14, so in one case the controller is driven more rapidly for a given movement of the handle than in the other case. The handle 10 is secured to a frame composed of disks 17 and 18 pivoted at 10', the former having a flange 19 to which the handle is secured by studs 20 which pass

through projections on the handle and are tapped onto the flange. The handle may be secured at various points around the flange 19 as shown. The frame operated by the handle carries a pawl 21 which engages with the teeth of ratchet sector 12. This pawl is mounted on a pin which is secured in lugs 22 on the disks 17 and 18. The forward movement of the handle, therefore, will cause the pawl 21 to engage the ratchet sector 12 which will drive the controller shaft through the gear 13 and pinion 14. This operation may be continued by moving the handle 10 backward and forward in a well understood manner.

For operating the controller shaft 11 at a higher speed by a continuous movement of the handle 10 the gear sector 15 is loosely mounted on the pivot shaft 10' which in turn is mounted in a stationary bracket 23. The shaft also carries the ratchet sector 12 and gear 13. This gear sector 15 is driven by the handle through two stops 24 and 25 secured on the inner side of the disk 17. These stops engage the ends of the sector 15 and push it either forward or backward depending upon which stop is in engagement. There is a lost motion between the stops and the gear which represents substantially the distance which the handle 10 moves when the handle is moved back and forth in ratcheting, and the pivoted handle, the frame with the stops, and the gear sector 15 comprises a lost motion driving connection for moving the controller continuously at a higher rate of speed than when the handle is reciprocated. Upon further movement beyond the one ratchet step, the stop engages the sector and the controller is then driven at a higher speed with a continuous movement.

It will be understood, of course, that since the gears on the controller shaft are always in mesh with the operating gears, when the controller shaft is driven through one pair of gears the controller shaft also drives the other pair of gears. In other words, suppose that the controller shaft is being driven by the pawl through ratchet sector 12 and gears 13 and 14, the controller shaft is, of course, also turning the gear sector 15; so that the gear sector 15 rotates at a faster rate than that at which the gear 13 is rotated. This makes it neces-

sary that on the return movement of the controller, which is accomplished by a continuous movement of the operating handle, the pawl 21 be withdrawn from the ratchet 5 segment so that the latter may return. The arrangement whereby this is accomplished is shown in Fig. 3, from which it will be seen that there is a pin 26 secured in the end of the gear sector 15 which pin engages 10 a lug on the pawl 21 to force it out of engagement with the teeth on the ratchet sector 12 against the tension of a spring 27 which is seated between the lug on the pawl and the lug 28 on the disk 17. As the handle returns, therefore, the pawl will engage with the pin 26 and be forced out of the path of the ratchet teeth so that the ratchet sector 12 which on the return movement 15 will be moving more rapidly than the gear sector 15, will be free to pass.

In order to insure that during the step by step forward movement of the controller, movement will be limited to a single step upon each reciprocation of the handle, I 20 have provided an arrangement shown in detail in Fig. 4. This arrangement includes a pawl 29 pivoted at 30 in the flange 19 of the disk 17. This pawl is adapted to engage teeth 30' of the stationary sector 31 25 secured to the frame. This pawl has a tail piece 32 which is engaged by a pin 33 which lifts the pawl out of the path of the teeth 30'. The inner surface of this tail piece is slightly eccentric so that as the pin 33 moves 30 toward the pivoted center of the pawl the opposite end of the pawl which engages the teeth will be lifted. Pin 33 is secured to the gear sector 15 by means of an arm 34 extending outwardly, the pin projecting 35 through a slot 35 in the disk 17 to engage the pawl. The result is that as the handle 10 is moved forward, the pawl will be lowered, since the tail piece gradually leaves the pin 33 and will finally be released entirely 40 so that the pawl will engage the tooth. As the handle is moved backward, the pawl will be again lifted by engaging with the pin. When the handle is moved forward the next time however, the pin 33 has moved 45 forward somewhat, since it is connected with the gear sector 15, so that the pawl will not be released until the first tooth is passed. It will then drop into the second tooth. This operation may be continued, each reciprocation 50 of the handle bringing the pawl into engagement with a succeeding tooth, and, consequently, permitting the handle to move forward step by step and hence driving the controller forward in the same way. 55 I have provided a releasing handle 36 provided with projection 37, which engages a similar projection 38 on the pawl. This is for the purpose of lifting the pawl out of 60 engaging position with the teeth, so that if desired, the step-by-step movement will not

be forced upon the operator. In other words, if desired, he may by forcing the handle forward, move the controller shaft at a higher speed through the gears 15 and 16 with a continuous movement.

As thus constructed and arranged the operation of my invention is as follows: Assume the parts in the position as shown in the drawings, the pawl 32 being released by the handle 36 so that it is in operative position, the pawl 21 will move forward and engage a tooth on the ratchet sector 12 and carry the ratchet sector forward (in a clockwise direction Fig. 1). This will rotate the controller shaft through the gear 13 and 70 pinion 14 (in a counter clockwise direction, Fig. 1). As the handle moves forward the pawl 32, of course, moves forward, and although the pin 33 is also moving forward slowly, the pawl is moving faster until 75 finally, when the tooth on the pawl is adjacent the first of the teeth 30' the pawl is released and is locked against further movement by the first tooth 30'. During this movement the stop 24 has approached the 80 end of the gear sector 15 but has not quite reached it. The controller has now been moved forward one step. To move another step, the handle 10 is moved backward carrying the pawl 21 back until it engages 85 the next tooth in the ratchet sector. Upon this movement the pawl 32 is again raised by engagement with the pin 33, but this time it will be observed that the pin 33 having advanced somewhat during the previous forward movement of the handle will 90 engage the tail piece of the pawl in a more forward position. On the next step forward, therefore, the tail of the pawl will not be released when the pawl is adjacent 95 the first tooth, but the pawl will be kept raised until it comes adjacent the second tooth 30', so that the handle may now be moved forward a distance corresponding to 100 the second tooth 30'. As the handle 10 is 105 moved back and forth this movement forward of the pawl, and consequently of the controller shaft continues step by step. To return the controller to "off" position after 110 this step-by-step movement the handle 10 is moved in a counter clock-wise direction 115 in a continuous movement. This movement of the handle causes the stop 25 on the disk 17 to engage the end of the gear sector 15 (see Fig. 3) and also causes the lug on pawl 120 21 to engage the pin 26 on the gear sector, thereby moving the pawl out of engagement with the teeth on the ratchet sector. The controller will now be moved rapidly, since the stop 25 pushes the gear sector 15 which 125 meshes with gear 16 and drives the shaft 11. While this movement is taking place, it will be noted that the gear 14 is driving gear 13 and the ratchet sector 12 backward at a faster angular velocity than that of the 130

gear sector 15, but since the pawl 21 has been raised out of engagement with the teeth of the ratchet sector the latter is permitted to pass. Where the step by step operation is employed, therefore, the operator is limited in his forward direction to a step by step movement, whereas in a return direction the controller is moved rapidly with a continuous movement.

10 If it is desired to operate the controller with a continuous movement of the handle in both directions the handle 36 is moved to the dotted position (Fig. 4) so as to hold the pawl in Fig. 2 in a raised position. The operator in moving forward, therefore, may now move the handle until the stop 24 engages the end of the gear sector 15 and then by employing pressure to the handle 10 the gear sector will be moved forward by the 15 stop and the controller moved forward through the pinion 16. This movement will be at a relatively high rate of speed because of the higher gear ratio between the gear sector 15 and the pinion 16 and obviously 20 the operator must apply more pressure to the handle to effect this operation. The return movement of the controller is the same 25 as that above described.

It will thus be seen that I have provided 30 a controller in which a step by step operation is forced upon the operator or which if desired may be adjusted to permit a continuous rapid movement of the controller. Either mode of operation may be selected.

35 While I have described my invention as embodied in concrete form and as operating in a specific manner in accordance with the provisions of the patent statutes, it should be understood that I do not limit my invention thereto, since various modifications 40 thereof will suggest themselves to those skilled in the art without departing from the spirit of my invention, the scope of which is set forth in the annexed claims.

45 What I claim as new and desire to secure by Letters Patent of the United States, is:

1. A controller for electric motors comprising a controlling member an operating member therefor, means whereby a reciprocating movement of the operating member causes a step by step forward movement of the controlling member over a predetermined range and means whereby a continuous forward movement of the operating member causes a continuous forward movement of the controlling member over said range.

2. A controller for electric motors comprising a controlling member an operating member therefor, means whereby a reciprocating movement of the operating member causes a step by step movement of the controlling member over a predetermined range and means whereby a continuous movement of the operating member causes

a continuous movement of the controlling member over said range at a higher rate of speed than in the step by step movement for a given speed of the operating member.

3. A controller for electric motors comprising a controlling member an operating member geared thereto at two different gear ratios and means whereby a reciprocating movement of the operating member drives the controlling member at one gear ratio 70 and a continuous movement of the operating member drives the controlling member at the other ratio.

4. A controller for electric motors comprising a controlling member an operating member geared thereto at two different gear ratios and means whereby a reciprocating movement of the operating member drives the controlling member in one direction at one gear ratio and a continuous movement 80 of the operating member drives the controlling member in the opposite direction at the other gear ratio.

5. A controller for electric motors comprising an operating member, a controlling member, a ratchet and pawl connection between the operating member and the controlling member for driving the controlling member in one direction and means whereby a continuous movement of the operating 90 member renders the ratchet and pawl drive inoperative and causes a continuous movement of the controlling member.

6. A controller for electric motors comprising a controlling member, an operating 100 member having a lost motion geared driving connection therewith and means whereby a reciprocating movement of the operating member within the range of the lost motion causes a step by step movement of the controlling member at a gear ratio which differs 105 from that of the lost motion drive.

7. A controller for electric motors comprising a controlling member, two gears secured thereto, a driving gear for each of said 110 gears, an operating member, a lost motion driving connection between the operating member and one of said driving gears and a ratchet and pawl driving connection operable within the range of the lost motion between the operating member and the other 115 driving gear.

8. A controller for electric motors comprising a controlling member, an operating member having a lost motion driving connection therewith, means whereby a reciprocating movement of the operating member within the range of the lost motion causes a step by step movement of the controlling member and means whereby the movement 120 of the operating member may be either limited to the reciprocating movement or may effect a movement of the controlling member through the lost motion driving connection.

9. A controller for electric motors comprising a controlling member, two gears secured thereto each having a coöperating gear for driving the controlling member at different gear ratios, a lost motion driving connection between the operating member and the gear having the higher gear ratio, a ratchet and pawl driving connection, operable within the range of the lost motion, between the operating member and the other driving gear and means for rendering the ratchet and pawl connection inoperable when the lost motion has been taken up and the controlling member is driven at the high gear ratio.
10. A controller for electric motors comprising a controlling member, two gears secured thereto, a driving gear meshing with one of said gears at a relatively high gear ratio, a driving gear meshing with the other gear at a lower gear ratio, a lost motion connection between the operating member and the operating gear having the high gear ratio, a ratchet and pawl connection, operable within the range of the lost motion, be-

tween the operating member and the other operating gear and means for moving the pawl out of operative relation when the lost motion has been taken up and the controller is driven at the high gear ratio.

11. A controller for electric motors comprising a controlling member, an operating member therefor, means whereby a reciprocating movement of the operating member causes it to advance a step on each reciprocation and move the controller a corresponding step, a pawl movable with the operating member, a member having teeth arranged to be engaged by the pawl to stop the movement of the operating member and means advancing with the controlling member for lifting the pawl out of engaging relation with the teeth in the backward movement of the operative member so that the pawl will be released in a more advanced position and engage a succeeding tooth at each reciprocation.

In witness whereof, I have hereunto set my hand this 14th day of August, 1918.

CLARENCE T. CROCKER.
